UNITED STATES PATENT OFFICE.

JOHN R. HARRINGTON, OF BROOKLYN, NEW YORK.

IMPROVEMENT IN MACHINES FOR MAKING CARPET-LINING.

Specification forming part of Letters Patent No. 122,381, dated January 2, 1872; antedated December 16, 1871.

To all whom it may concern:

Be it known that I, JOHN R. HARRINGTON, of Brooklyn, in the county of Kings and in the State of New York, have invented a new and useful Machine for Making Carpet-Linings; and I do hereby declare that the following is a full, clear, and exact description thereof, reference being had to the accompanying drawing forming a part of this specification.

My invention consists in a combination of feed-rollers, presser-rollers, drying-rollers, folders, and brushes and paste-troughs, for the purpose of rapidly making carpet-linings, composed of two continuous sheets of paper with a sheet of filling between them.

In the drawing, Figure 1 represents a side elevation; Fig. 2, a plan view; Fig. 3 shows the "folder" for folding over the "double-lap binding," shown in Fig. 5. Fig. 4 shows the folder for folding in the edge of the under sheet of paper in the "turned-in binding," shown in Fig. 7. Fig. 5 is a section showing the "double-lap binding." Fig. 6 shows the "welt-binding." Fig. 7 shows the "turned-in binding." Fig. 8 shows the "strip-binding."

It will be seen that my machine is capable of making four or more different kinds of lining.

In the drawing, A represents the general frame-work of the machine, oblong square in shape, and may be about three feet high and wide, and about twelve or fifteen feet long. B B' are the two paper-feed rollers; C is the filling or wadding feed-roller; D D' are the feed-bobbins for the "double-lap" binding; F F' F'' are the brushes for applying the paste to the outer edges of the two sheets of paper when the double binding is used, and G is the paste-trough, used in connection with these brushes. H H' are the folders which fold the binding over the edges of the paper; I I' are the folders which turn in the edges of the under sheet of paper in making the "turned-in" binding; J J' are the bobbins which carry the strips of paper or cloth used in the "welt-binding" or "strip-binding." K is the paste-trough for pasting the "strips;" L is a large roller, revolving in and nearly filling the trough K; M M' are presser-rollers; N O P are three large drying-rollers, at the delivery end of the machine; Q is the last or discharge-roller. The various rollers and brushes are properly revolved by

belts in any suitable and obvious manner.

I will describe the mode of operation in making each of the four kinds of carpet-lining shown in the drawing.

In making the carpet-lining with the "double-lap" binding, described in my patent of September 27, 1870, I first put two continuous sheets of suitable paper upon their feed-rolls B B', and a continuous sheet of filling upon its feed-roll C, and the strips of cloth or paper for binding upon the bobbins D, and fill the paste-troughs G with a suitable paste. The machine is then put in motion. Until the first two or three yards of the lining have been made the operators, by hand, feed forward the lining until it is taken between the feed and presser-rollers M M'. As the paper leaves the feed-rollers it passes between the lips of the brushes F, which apply the paste to the edges of the paper, as shown at x, Fig. 2. The paper or cloth strips on the bobbins D then pass through the folders H, which fold them over the paper on the edges where the paste has been applied; the presser-rolls M M' then press closely the folded strips up on the paper, which thus becomes securely fastened and closed at both edges. The lining is then passed over the drums N O P and roller Q, ready to be baled.

In making carpet-lining with the "welt-binding," as shown in Fig. 6, I dispense with the use of the brushes F and paste-trough G. I use only three strips of paper or cloth, one at each edge and one at the center of the lining. These strips pass under roller L, and are thus immersed in the paste which is contained by the trough K; they then pass onward, between the two sheets of paper, one at each edge, between the sheets of paper past the edges of the filling, and continue to go forward with the paper and the filling until they all pass between the presser-rollers M M', which press and stick together the strips, paper, and filling, and carry forward the completed lining to the drying-rollers N O P.

It will be seen that the brushes F are of a peculiar construction, the brush at each end of the trough being really a triple brush; that brush marked F revolving vertically in the paste for the purpose of feeding the brushes F' and F''. These brushes F' and F'' are in a horizontal plane, and have their faces touch-

ing, so that when the paper passes between them it will be pasted on both sides. These brushes may be used together, or the brush F^2 may be unshipped; they mesh with brush F , and are revolved by it like bevel-gearing.

In making the "turned-in" binding, shown in Fig. 7, the under sheet of paper must be about two inches wider than the upper, to allow about an inch to be turned in at each edge. The brush I^2 is unshipped, in this case, and the folders I are used to turn in the edges. As the paper goes forward the under face of the brush F^1 applies the paste to the upper surface of the folded edge. The presser-rollers M then press and stick together the two sheets of paper with the filling between them, as shown in Fig. 7.

In making the "strip-binding" lining, shown in Fig. 8, (for which I have prepared another specification and application,) I dispense with the use of the folders, brushes, and trough G , and use instead four, six, or more narrow strips, $a a$, of paper or cloth disposed in pairs. When six of these strips are used, as shown in the drawing, Figs. 1 and 2, three of them pass between the filling or wadding and the under

sheet of paper, and three (but not opposite) between the wadding and the upper sheet of paper. Being well pasted on both sides these strips stick as well to the wadding as to the paper, when they are passed between the presser-rolls.

What I claim as my invention is—

1. The mitre-brushes $F F^1$, in combination with the paste-trough G .
2. The folders $H H$, in combination with bobbins $D D$ and presser-rolls $M M$.
3. The folders $I I$, in combination with brushes $F F^1 F^2$ and presser-rolls $M M$.
4. The bobbins $J J$, in combination with trough K , roll L , and presser-rolls $M M$.

In testimony that I claim the above-described invention for machine for making carpet-lining, I have hereunto signed my name this 3d day of October, 1870.

JOHN R. $\times$ HARRINGTON.
